UNITED STATES PATENT OFFICE

2,448,948

IRONING MACHINE

Henry H. Babcock, Oak Park, Ill., assignor, by
mesne assignments, to Conlon-Moore Corpora-
tion, Cicero, Ill., a corporation of Delaware

Application June 19, 1944, Serial No. 540,907

15 Claims. (Cl. 38—61)

1

This invention relates to ironing machines, and has to do with domestic ironing machines intended for home use.

In patent No. 2,346,374, issued April 11, 1944, to Frederick M. Freis, there is disclosed an ironing machine in which the motor is housed within the roll and drives the latter, while also operating the shoe for moving it to and from the roll, which is supported for rotation on a bracket structure secured to the gear housing. The instant invention is directed to an ironing machine having the motor housed within the roll and effective for driving the latter and for operating the shoe, the motor also serving as part of the means for supporting the roll. Also, I take advantage of the positioning of the motor within the roll for drawing air through the padding of the roll so as to avoid excessive dampness thereof, thereby assuring that articles being ironed are properly dried in passing through the machine, which is conducive to increased speed in ironing. An additional feature of my invention is the provision of shoe coupling and release means operable from in front of the machine, adapting it for use with a cover having a rearward shoe enclosing section normally stationary on the stand or supporting structure of the machine. I also provide improved means for driving the roll and operating the shoe from the motor housed within the roll, directed to simplification of construction and reduction in the number of parts employed. Further objects and advantages of my invention will appear from the detail description.

In the drawings:

Figure 1 is a front view of an ironing machine, with the front section of the cover in open position, embodying my invention;

Figure 2 is an end view of the machine of Figure 1, with the cover omitted and the gear housing cover removed, partly broken away and on an enlarged scale;

Figure 3 is a sectional view, on an enlarged scale, taken substantially on line 3—3 of Figure 2, certain parts being broken away and certain other parts being shown in elevation;

Figure 4 is an inner side view of the gear housing;

Figure 5 is a sectional view taken substantially on line 5—5 of Figure 3;

Figure 6 is a sectional view, on an enlarged scale, taken substantially on line 6—6 of Figure 2, certain parts being shown in elevation;

Figure 7 is a sectional view taken substantially on line 7—7 of Figure 6;

2

Figure 8 is a sectional view, taken substan-
tially on line 8—8 of Figure 6;

Figure 9 is a sectional view taken substan-
tially on line 9—9 of Figure 1;

Figure 10 is an inner end view of the motor
casing;

Figure 11 is a view partly in section and partly
in front elevation of the gear housing and the
parts therein, showing a modified form of roll
drive and shoe operating means;

Figure 12 is an outer side view of the gear
housing and associated parts of Figure 11, with
the housing cover removed and the lower portion
of the housing shown in section; and

Figure 13 is a sectional view, on an enlarged
scale, taken substantially on line 13—13 of Figure
12, certain parts being shown in elevation.

I have illustrated my invention, by way of
example, as embodied in an ironing machine
20 comprising a support or stand 20 having a top
plate 21 of channel section both lengthwise and
transversely, with end frames or legs 22, of
suitable construction, rigidly secured to and ex-
tending downward from plate 21 at each end
thereof. A gear housing 23 extends upward from
plate 21 at one end—the right end as viewed in
Figure 1—thereof, the lower portion of housing
23 extending downward through plate 21 be-
tween reinforcing angle members 24 and 24^a, spot
welded to the underface of plate 21, to which it is
bolted (Figures 2, 3 and 9). A roll 25, sup-
ported from gear housing 23 in a manner here-
inafter described, extends inwardly over cloth
pan or top plate 21 in spaced relation thereto.
35 A hot shoe 26 is supported in back of roll 25 for
movement to and from the latter, by means
which will be described herein later.

The support or stand 20 is intended to be pro-
vided with a box-like cover 27, comprising a sta-
tionary rearward section 28 and a forward mov-
able section 29 hinged at 30 to section 28. When
section 29 is in its open position shown in Fig-
ure 1, it provides an open front open top tray
readily accessible from in front of the machine
45 for reception of ironed articles. A flat lid 31 is
suitably mounted on cover section 28 for move-
ment into a substantially vertical position, per-
mitting opening of cover section 28, as shown,
and movement into a horizontal position resting
upon cover 27, when section 29 thereof is closed,
providing a continuous top surface for the cover
structure available for use as a table top. When
the forward cover section 29 is closed it provides
in cooperation with section 28 a box-like hous-
55 ing enclosing the roll 25 and shoe 26 and asso-

ciated parts above plate 21. The cover 27 and related features constitute the subject matter of my copending application for Ironing machine, Serial No. 539,268, filed June 8, 1944, now Patent No. 2,413,427, issued on December 31, 1946, and need not be described in greater detail here.

Referring to Figure 3, gear housing 23 has a main inner side wall 32 from the upper portion of which projects a semicircular neck 34 merging at its lower ends into a supplementary inner side wall 35, having a lower portion 35* inclined downwardly and inwardly toward plate 21 and provided, at its lower end, with a vertical flange 36. Supplementary inner side walls 35—35*—36 are connected by a wall 37 at the front and the back thereof, respectively, to the front and the back walls of gear housing 23. The walls 35—35*—36, 37 and 32 define a passage 38 having a restricted upper portion opening into neck 34 and a downwardly flaring portion opening below top plate 21, a short distance above the bottom of gear housing 23. Wall 35 is provided at its upper portion with a semicircular recess 39 (Figure 4) of less diameter than and concentric with neck 34. A horizontal flange 33 extends along flange 36 and the front and back walls of gear housing 23, and seats on top plate 21 about the opening therein through which the lower portion of the gear housing extends.

An electric motor 40 of suitable type is bolted to the inner side of gear housing 23 in concentric relation to neck 34, with the outer end of its casing 41 seating tightly against the inner end of neck 34 and the inner face of wall 35. Motor casing 41 is of sufficient mechanical strength to serve as a load supporting member for the roll, and has the outer surface of its outer end portion 41* accurately formed so as to be concentric with neck 34, into which it freely opens as shown. A fan 42 is secured upon shaft 43 of motor 40 for drawing cooling air therethrough, as is known, this fan also serving to discharge air through the outer end of motor casing 41 and thence into and through the passage 38. Motor shaft 43 is coaxial with a stub shaft 44, which is the main drive shaft of the machine, rotatably mounted in a bushing 45 through wall 32 of gear housing 23, with stop collars 46 secured thereon and contacting the inner and outer faces of wall 32 forming a substantially air tight seal about shaft 44, for a reason which will appear presently. The stub shaft 44 is connected to motor shaft 43, so as to be driven thereby, by a flexible connector 47 of any suitable known type, which accommodates any slight misalignment of the shafts. It will be understood, from what has been said that the motor casing 41 is open at its inner end, as is known and as shown in Figure 10, for free flow of cooling air therethrough.

An inwardly flaring sleeve 48, formed of any metal or alloy of requisite mechanical strength and weight, is bolted at its outer end, by means of an inner circumferential flange 49, to the inner end of motor casing 41 about the opening thereof. A bearing retaining ring 50 is secured to the inner end of sleeve 48, adjacent the inner end of perforated metal cylinder 51 of roll 25, which comprises cylinder 51, a coarsely woven fabric pad 52 wound thereon, and a relatively finely woven fabric pad cover 53 wound over pad 52, the structure of the roll as a whole being such as to permit ready flow of air therethrough radially thereof. The sleeve and the flange 49 and the ring 50 may be fabricated, as shown, or may be formed as a single piece, as desired. The retaining ring 75

50 receives a ball bearing structure 54 of known type, fitting snugly, but not too tightly, between the radially inward arm of ring 50 and roll cylinder 51. A second retaining ring 55 screws into 5 a collar 56 welded or otherwise suitably secured in ring 50. Ring 55 is provided at its inner end with a circumferential flange 57 extending radially outward thereof at the inner side of ball bearing structure 54 and of a width to overlap the 10 outer race of the latter. A ring 58 of leather or other suitable material, impregnated with a lubricant to avoid objectionable friction, is disposed between flange 57 and the ball bearing structure 54, the arrangement being such as to provide a 15 substantially air tight closure between the inner end of sleeve 48 and the roll cylinder 51. It will be noted that the radially inner arm of ring 58 extends a short distance beyond the ball bearing structure 54, toward the adjacent end of roll cylinder 51, serving as a stop for flange 57 and preventing the sealing ring 58 from being forced into binding contact with the ball bearing structure. The ring 58 is not essential and may be omitted where the parts are fitted sufficiently accurately 20 to prevent objectionable leakage of air therethrough. Preferably, though not necessarily, a screen 59 may be provided in the inner end of roll cylinder 51, having a friction fit therein.

A bearing race 60 is spot welded or otherwise 30 suitably secured in roll cylinder 51, a short distance from the outer end thereof, in cooperating relation to a second race 61 suitably secured on the motor casing 41. The races 60 and 61 receive between them bearing balls 62 conveniently 35 mounted in a suitable cage 63. An internal ring gear 64 is welded or otherwise suitably secured in roll cylinder 51, and has an outwardly extending portion free of gear teeth. Two sectional metal rings 65, clamping between them a sealing ring 66 40 of felt, leather or other suitable material, are secured in a suitable manner, as by means of screws, to the outer end of ring gear 64. The ring 66 fits snugly about motor casing 41 so as to provide a substantially air tight seal thereabout. The 45 sealing ring 66 may be impregnated with a suitable lubricant, if found desirable, to avoid objectionable friction, and, within the broader aspects of my invention, any other suitable means may be provided for effecting a substantially air tight 50 closure between the outer end of the roll cylinder and the motor casing. It will be seen that the motor 40 and the sleeve 48 support the roll, the sleeve providing a funnel for supplying air in adequate amount to the motor, and that the space 55 67 between sleeve 48 and roll cylinder 51 has a decided taper inwardly lengthwise of the latter and is closed substantially air tight at each end. The ball bearing structures at each end of the roll serve both as radial and thrust bearings and support the roll for rotation about the common 60 axis of motor 40 and sleeve 48.

Motor casing 41 is provided, at the lower portion of its outer end, with an arcuate recess extending radially inward thereof and defining a pocket 69 partly closed at its lower side by an arched plate 70, seating at its ends in recesses in casing 41 and secured thereto by screws, the outer face of the plate 70 merging into and forming a continuation of the outer circumferential surface of end portion 41* of casing 41, in the area of the sealing ring 58. Plate 70 is of materially less width than the length of pocket 69, which receives in its inner portion a spur pinion 71 meshing with ring gear 64. Pinion 71 is secured on the inner end of a roll drive shaft 72

rotatably mounted in bosses 73 and 74 of walls 32 and 33, respectively, and driven from the motor 40 in proper direction for rotating roll 25 in clockwise direction as viewed in Figure 2.

A worm 75 is secured on the outer end of stub shaft 44 and meshes with a worm wheel 76 secured on a horizontal shaft 77 rotatably mounted at one end in a boss 78 of gear housing 23, the other end portion of this shaft being rotatably mounted in a short sleeve 79 (Figure 6) rotatably mounted in two adjacent bearing bosses 80 projecting outward from wall 32, each provided at its outer end with a removable cap plate 81. Sleeve 79 is provided with a disc 82 at its outer end and, intermediate its ends, with an eccentric 83 fitting between bosses 80 and in cooperation therewith restraining sleeve 79 against endwise movement. A bevel gear 84, loose on shaft 77, at the opposite side of worm wheel 76 from sleeve 79, has secured thereto a clutch member 85 which cooperates with a clutch member 86 feathered on shaft 77 between boss 78 and bevel gear 84. A shift lever 87, pivoted at 88 on a lug 89 projecting from the front wall of gear housing 23, has operating connection at its upper end, in a known manner, to clutch member 86. Lever 87 has pin and slot connection 90, at its lower end, to the rearward end of a rod 91 slidable through a boss 92 of the front wall of gear housing 23, there being a knob 94 secured on the outer end of rod 91. It will be seen that when motor 40 is in operation the shaft 77 is driven continuously and bevel gear 84 may be clutched to and declutched from shaft 77 so as to be driven thereby or not, as desired. Bevel gear 84 meshes with a bevel gear 95 secured on the upper end of a vertical stub shaft 96 (Figure 3) rotatably mounted through a bearing boss 97 projecting outwardly from wall 32 of gear housing 23. A bevel pinion 98, secured on the lower end of shaft 96, meshes with a bevel pinion 99 secured on the outer end of the roll drive shaft 12. It will be apparent that the drive of the roll is controlled by the roll clutch means, comprising the clutch members 85 and 86 and the shift means for the latter member. Any other suitable means may be provided for clutching and declutching bevel gear 84 to and from shaft 77, within the broader aspects of my invention.

It will be noted from Figures 3 and 5 that the opening through the outer end of motor casing 41 is somewhat constricted, and that casing 41 is provided in that constricted area with a plurality of circumferentially spaced slots 100 opening at their radially outer ends into space 67, these slots flaring inward to produce a venturi effect. When the motor 40 is in operation, the fan 42 draws air through the motor and discharges this air under considerable velocity through the outer end of casing 41. The air flowing over the inner ends of openings or slots 100 induces air therethrough from space 67, producing a partial vacuum in the latter effective for inducing air through the roll pad 52 and cover 53. The inward taper of space 67 lengthwise of the roll assures that air will be drawn through the roll substantially uniformly throughout the length thereof. In that manner steam generated during the ironing operation, by the action of the hot shoe on the damped articles being ironed, is withdrawn from the roll pad and discharged with the air beneath the top plate 21. This continuous withdrawal and discharge of the steam, before it has been absorbed by the pad to an appreciable extent, assures that the roll is

maintained in a substantially dry condition, which avoids objectionable drag or resistance to rotation of the roll when ironing due to excessive dampness of the roll pad, which is conducive to more rapid ironing with the expenditure of less power for driving the roll.

Referring to Figures 1, 2, 3, 6 and 7, eccentric 83 of sleeve 79 receives thereabout an eccentric strap 101 secured to the upper end of an arm 102 operating in slotted guide lugs 103 projecting outward from wall 32 of gear housing 23. The lower end of arm 102 is attached by a universal connection 104 to the forward end of a shoe shaft operating arm 105, which is fixed at its rearward end on the outer end of a shoe operating shaft 106 rockably mounted in a sleeve 107 disposed in back of and parallel with roll 25 and adjacent top plate 21. Sleeve 107 is secured at its outer portion in a relatively short sleeve 108 integral with gear housing 23, and has its inner end secured in a tubular bracket 109 bolted or otherwise suitably secured to top plate 21. By rotating sleeve 79, and with it eccentric 83, the shoe operating shaft 106 is rocked in alternately opposite directions and to proper extent for moving the shoe 26 to and from the roll 25.

I provide half revolution clutch means for clutching and declutching sleeve 79 to shaft 77 at appropriate times. Any suitable clutch means may be provided within the broader aspects of my invention, though I preferably employ clutch means similar to that disclosed in Patent No. 1,867,839, issued July 19, 1932, to Rudolph W. Janda, for ironing machine, a brief description of which will suffice here. Disc 82 is provided with an outwardly projecting flange 109 (Figure 6) concentric with shaft 77, the outer face of disc 82 being flat or planar outwardly beyond flange 109. Disc 82 is further provided, in its outer face and adjacent flange 109, with a channel 110 of appreciable depth, which receives a tension coil spring 111. One end of spring 111 is anchored by a pin 112 to disc 82. At its other end spring 111 has an eye 113 (Figure 7) which hooks over a tongue 114 struck inward from a clutch operating ring 115 fitting about flange 109 and seating upon the outer face of disc 82, providing a closure for the outer side of channel 110. An annular clutch yoke 116, of laminated construction, is disposed about flange 109 and seats upon ring 115. This yoke is provided with diametrically disposed notches 117 which receive angularly disposed tabs 118 formed integrally with and projecting outwardly from ring 115, these tabs being outwardly offset radially of the body portion of the ring.

A star wheel 119, also of laminated construction, is disposed within the pocket or recess defined by flange 109 and fits snugly about the adjacent squared end portion 120 of shaft 77. A cover disc 121 fits about squared portion 120 of shaft 77 and is confined between the outer face of flange 109 and an outer retainer disc 122 secured by a screw 123 to the end of shaft 77. The length of squared portion 120 of shaft 77 is such, relative to the length of flange 109 and the thickness of star wheel 119, that disc 121 has but light contact with flange 109 and star wheel 119, insufficient to cause objectionable friction or drag between these parts. Disc 121 serves to hold the clutch parts in proper cooperating assembled relation, as will readily be understood. Flange 109 has a slot 124 therethrough which receives a clutch disc 125 of a size and shape to fit into notches 126 of star wheel 119. Clutch

yoke 116 is provided, in its inner edge, with a recess 127 of proper depth to receive the portion of disc 125 which projects outwardly beyond flange 109, when this disc is in its outer or inoperative position clear of star wheel 119, shown in Figure 8. The spring 111 urges ring 115 in clockwise direction.

A trip member 128, disposed in back of shaft 77, is pivoted between its ends, at 129, in a lug 130 projecting outward from wall 32 of gear housing 23. Member 128 is provided with a trip finger 131, at its upper end, projecting outwardly therefrom. A compression spring 132, confined between finger 131 and wall 32, with its ends seating about centering studs carried by wall 32 and finger 131, in a known manner, urges trip member 128 in clockwise direction, as viewed in Figure 3, about its pivot 129 and normally holds finger 131 in the path of travel of the trip tabs 118 of the clutch operating ring 115. The lower portion of trip member 128 operates in slotted guide lugs 133 projecting forward from wall 32, and this member is provided at its lower end with a foot element 134. A control rod 135, slideable through wall 32 and flange 36 normally is held in its inner or retracted position by a compression spring 136 disposed thereabout and confined between wall 32 and a stop collar 137 secured upon rod 135 and abutting flange 36. Rod 135 is disposed for contact at its outer end with foot element 134 and has pin and slot connection 138 at its inner end (Figure 9) to a trip lever 139 pivoted at its rearward end, at 140, to a bracket 141 secured to the central reinforcing angle member 24. Lever 139 extends forward to within a short distance of the front of top plate 21 and is provided at its forward end with a downwardly extending arm 142 having a covering or pad of rubber or the like. The arm 142 is disposed adjacent the right hand end of the machine (Figure 1), in position to be readily actuated by the right knee of an operator seated in front of the machine.

With the parts in their positions shown in Figures 2 and 8, the eccentric 83 is in its lower position and the arm 102 has been moved downward, depressing the forward end of arm 105 and turning shaft 106 in counterclockwise direction, thereby moving the shoe 26 into its forward position shown, into operating relation with the roll 25. One of the tabs 118 is then in contact with trip finger 131, spring 111 is under tension, the recess 127 of clutch yoke ring 116 is in alignment with slot 124 of flange 109, and clutch disc 125 is disposed above shaft 77 and clear of star wheel 119, with its outer portion within recess 127. A spring pressed plunger 143 is mounted in flange 109, at the left side of slot 124 thereof, as viewed in Figure 8, and contacts clutch disc 125 below the center thereof, yieldingly urging it outward and retaining it in its outer or inoperative position. The clutch yoke ring 116 is provided with an extension 127^a of recess 127, of less depth than the latter, for a purpose which will appear presently. It will also be noted that with the parts in their positions shown in Figure 8, the tabs 118 of clutch operating ring 115 are in contact with the following edges of notches 117.

In order to move the shoe away from the roll, trip lever 139 is swung to the right, thereby swinging trip member 128 in counterclockwise direction (Figure 3) and withdrawing trip finger 131 from beneath the trip tab 118 in contact therewith. The lever 139 is actuated but momentarily and is then released. When finger 131 is

moved clear of tab 118, clutch operating ring 115 is turned in clockwise direction (Figure 8) by spring 111, moving the tabs 118 out of contact with the following edges of notches 117 and into contact with the leading edges thereof. Spring 111 then urges clutch yoke 116 in clockwise direction, so that the wall of extension 127^a of recess 127 is brought into contact with clutch disc 125 and urges it inward. When one of the notches 126 of star wheel 119 comes into alignment with slot 124—assuming that shaft 77, and with it star wheel 119, is being rotated—spring 111 quickly turns yoke ring 116 in clockwise direction forcing disc 125 inward into operative or clutching position, this movement of disc 125 forcing the plunger 143 into its inner or retracted position. Thereafter, the clutch yoke ring 116 holds disc 125 in its inner or clutching position, clutching the sleeve 79 to star wheel 119, until sleeve 78 has been turned through one-half of a revolution. The other tab 118 then contacts trip finger 131, stopping rotation of clutch operating ring 115. The yoke clutch ring 116 continues to revolve with disc 82, tensioning spring 111 and bringing the following edges of notches 117 into contact with tabs 118, thus stopping rotation of clutch yoke 116. When that occurs, disc 82 continues to revolve, further tensioning spring 111, until slot 124 is brought into alignment with recess 127, at which time clutch disc 125 is forced into its outer or inoperative position, by the star wheel, and plunger 143 is projected and holds disc 125 in its outer position. The parts are then in their positions of Figure 8, except that the opposite tab 118 is in contact with trip finger 131, the eccentric 83 is in its upper position and clutch disc 125 is below shaft 77. The turning of eccentric 83 from its lower position to its upper position raises the forward end of arm 105, rocking shoe operating shaft 106 in clockwise direction (Figure 2) effective for moving the shoe 26 away from the roll 25. It will be apparent that by operating the trip lever 139 the shoe may be moved to and from the roll as desired. The plunger 143 assures that the clutch disc 125, when in position above shaft 77, will be held in its outer position, projecting into recess 127, guarding against objectionable clicking or chattering, due to disc 125 being struck by star wheel 119, or possible jamming of parts, such as might occur if the clutch disc 125 were not held in its outer position.

The shoe 26 is supported by an arm 147 loose on shaft 106 and straddling an arm 148 fixed on shaft 106. Suitable means is provided for coupling arm 147 to arm 148 for movement therewith, for moving the shoe to and from the roll in the operation of shaft 106, described above, and for quickly releasing arm 147 from arm 148 to permit of movement of the shoe rearward away from the roll independently of shaft 106. The coupling means is similar to that disclosed in the above Janda patent, and a brief description thereof will suffice. Arm 148 is slotted at its upper end for reception of the reduced neck of a coupling head 149 secured on the forward end of a rod 150 feathered in a thimble 151 screwing through a cruciform member 152 pivoted in shoe supporting arm 147, for rocking movement about a horizontal axis parallel with shaft 106. A compression spring 153, disposed about the rearward portion of rod 150, is confined between an adjusting knob 154, secured on the rearward end of rod 150, and a cup washer 155 abutting the rearward end of thimble 151 and free from rod 150. Member 152 has a downwardly extending slotted arm 156

in which is pivoted a bell crank latch member 157 disposed above a pin 158 secured in arm 147. When the arms 147 and 148 are coupled together, the parts are in their positions shown in Figure 2, and the shoe supporting arm 147 moves with shaft 166 for moving shoe 26 to and from roll 25. The shoe is under spring pressure, determined by the adjustment of thimble 151, when it is to the roll. By turning member 152 in clockwise direction (Figure 2) a proper distance, head 149 is disengaged from arm 148 and brought into contact with a slotted web 180 of arm 147, thereby uncoupling this arm from arm 148 and swinging it rearward about shaft 166 into a position limited by a stop 161 carried by bracket 189, whereby shoe 26 is moved rearward a greater distance than normal from roll 25. The coupling means so far described is similar to that of the above Janda patent and need not be described here in greater detail.

In order that the shoe supporting arm 147 may be coupled and uncoupled to and from arm 148 from in front of the machine, the member 152 is provided with an upwardly and rearwardly extending arm 162, in which is secured a shouldered screw 163 having a reduced shank 164 operating in slot 165 of an angularly shaped arm 166, fixed at its lower end on a stub shaft 167 rockably mounted in a bracket 168 secured, as by bolting, to top plate 21. The arm 166 and associated parts are so related that when this arm is swung in clockwise direction (Figure 2), the shank 164 of screw 163 is first subjected to a camming action effective for turning member 152 in clockwise direction, as above described, and thereafter the shoe supporting arm 147 is swung rearward away from roll 25. In this operation the bell crank 151 moves by gravity, as the shoe supporting arm 147 moves rearward, into position with end surface 169 of arm 170 thereof above and in front of pin 158, arm 171 of bell crank 157 then extending forward toward web 172 of arm 148; as in the above Janda patent. When arm 147 is swung in counterclockwise or forward direction (Figure 2) after the releasing operation described, the end surface 169 of arm 170 of bell crank 157 contacts pin 158 and shoe supporting arm 147 thereafter moves forward with arm 166. When coupling head 149 is properly positioned above and adjacent the upper end of arm 148, arm 171 of bell crank 157 contacts web 172 of arm 148, turning bell crank 157 in counterclockwise direction and releasing it from pin 158, after which member 152 turns in counterclockwise direction, in the continued movement of arm 166, so as to move the neck of head 149 into the slotted upper end of arm 148, completing the coupling operation, as in the above identified Janda patent.

A second arm 173 is secured on stub shaft 167, at the opposite end thereof from arm 166, and extends downward through a slot 174 in top plate 21. The lower portion of arm 173 is of increased width and is provided with a lengthwise slot 175 which receives a pin 176 secured in an arm 177 rigid with a collar 178 fixed on a rod 179 slidable through two of the reinforcing angle bars 24 (Figure 9). Rod 179 extends transversely of plate 21 and is urged rearward by a compression spring 180 disposed thereabout and confined between collar 178 and the central angle bar 24. At its forward end rod 177 has pin and slot connection 181 to one arm of a bell crank lever 182 pivoted at 183 on a bracket 184 secured to the adjacent angle bar 24. The other arm of bell crank

lever 182 is connected by a link 185 to the rearward end of release lever 186 pivoted at 187 on a bracket 188 secured to the front angle iron 24, adjacent the left end of the machine. Lever 186 has at its forward end a downwardly extending arm 189 provided with a resilient covering or pad of rubber or other suitable material. The arm 142 of trip lever 189 and the arm 189 of release lever 186 are disposed so as to be readily actuated by the right knee and the left knee, respectively, of an operator seated at the front of the machine. When the lever 186 is swung counterclockwise (Figure 9), the arm 186 (Figure 2) is swung clockwise, uncoupling arm 147 from arm 148 and swinging arm 147 rearward, in the manner above described. When shoe 26 has been moved rearward a short distance, in this uncoupling operation, it and arm 147 continue to move rearward by gravity until arm 147 contacts stop 161. During this rearward movement of shoe 26 and arm 147, the spring 180 is placed under increasing compression and serves as a cushion to retard rearward movement of arm 147, preventing it from striking stop 161 an objectionably hard blow such as to subject the machine to objectionable shocks or cause possible breakage of parts. The release lever 186 and associated elements thus provide for quick release of the roll from the shoe in the event the operator's fingers get caught between the roll and the shoe, or in the event such quick release becomes necessary for any other reason. In order to effect the recoupling operation, the operator grasps arm 189 of lever 186 with her hand and swings lever 186 in clockwise direction (Figure 9), swinging arm 186 counterclockwise (Figure 2), coupling arm 147 to arm 148 in the manner above described.

Referring to Figure 2, the gear housing 23 is provided with an interior switch box 190, preferably formed integrally therewith, at its lower forward portion. Switch box 190 opens through the front wall of gear housing 23 and receives a multiple switch block 191, of known type, conveniently carried by a mounting plate 192 secured in a suitable manner, as by screws, to the front wall of gear housing 23. The switch block 191 carries two switches, one for the motor and the other for the heating elements within shoe 26, each having an operating handle 194 extending through an opening in plate 192. An extension cord 195, provided with a plug cap 196 at one end, is led through the bottom wall of gear housing 23 into the switch box 190 thereof, and is appropriately connected to the switch block 191. A flexibly armored cable 197, connected to one of the switches of block 191, is led through the bottom wall of gear housing 23 and thence through top plate 21 to shoe 26, to the heating elements of which the wires of cable 197 are appropriately connected. A second flexibly armored cable 198, provided with a quickly detachable connector 199 of known type, is connected to the other switch of block 191, from which it is led through the bottom wall of gear housing 23, thence upwardly through passage 38 (Figure 3) into motor casing 41, through the latter outwardly of fan 42, along motor casing 41 to sleeve 48, and then through the wall of sleeve 48 and 70 into the inner end of motor 40, to which the wires of cable 198 are appropriately connected in a known manner. That provides means for establishing electrical connections from a suitable source of electrical energy, such as the house current, to the motor 40 and to the heating ele-

ments of shoe 26, under control of the respective switches of the switch block 191.

The gear housing 23 is provided, at its outer side, with an outer wall 200 extending upward a short distance above top plate 21, and the forward edge portion of gear housing 23 is thickened at 201. A lower cover plate 202 is secured over the outer side of gear housing 23, conveniently by screws, extending upward from wall 200. An upper and thinner cover plate 203, formed at its lower edge to provide a shoulder 203a seating on the upper edge of plate 202 and a depending lip 203b seating against the inner face of plate 202, is secured over the outer side of gear housing 23, also conveniently by screws. The plates 202 and 203 together constitute a removable cover for the outer side of gear housing 23 whereby access to the parts therein may readily be had. It will be understood that suitable sealing gaskets may be interposed between the gear housing and the cover therefor, though not shown.

In Figures 11, 12 and 13, the gear housing 23 is of substantially the same construction as gear housing 23 of Figures 1 and 2 and requires no detailed description. Worm 15, secured on stub shaft 44, meshes with worm wheel 204 mounted on a horizontal shaft 205 rotatably mounted in boss 206 of housing 23 and in a bearing boss 207 projecting outward from wall 32a of housing 23. A bevel pinion 208 is fixed to worm wheel 204, forming a unit therewith and this unit is confined between bearing boss 207 and stop collar 209 fixed on shaft 205, whereby both the latter and the unit 204—208 are restrained against endwise movement. The unit comprising worm wheel 204 and bevel pinion 208 may be loose on shaft 205 or keyed thereto as desired. Bevel pinion 208 meshes with a bevel pinion 210 fixed on the upper end of a vertical stub shaft 211 (Figure 13) rotatably mounted in a bushing 212 extending through a bearing boss 213 projecting outward from wall 32a. A bevel pinion 214, fixed on the lower end of stub shaft 211, meshes with a bevel gear 215 rotatably mounted on the outer end portion of roll drive shaft 216, mounted for rotation in a bushing 217 in a bearing boss 218 projecting outward from wall 32a.

The gear 215 constitutes an element of means for driving the roll shaft 216 at either of two speeds and for actuating the shoe operating shaft 106, from the motor driven stub shaft 44. Such means is similar to that disclosed in Patent No. 2,054,631, issued September 15, 1936, to Rudolph W. Janda, for Ironing machine, and a brief description thereof will suffice. Gear 215 is provided, at the outer portion of its hub 217, with a spur pinion 218, conveniently formed integral therewith. A ring member 219, mounted for relative rotation on hub 217, is provided with a first series of inner teeth providing an internal ring gear 220, a second series of inner teeth providing an internal clutch element 221, and, adjacent its inner end, with a series of teeth providing an external ratchet element 222. A disc 223 is fixed on the hollow outer end of shaft 216, at the outer end of hub 217, and shaft 216 slidably receives a hollow plunger 224 urged outward by a compression spring 225, confined between a disc 226 seating in shaft 216 and the plunger. Plunger 224 is provided with an outwardly tapering frusto-conical element 227 and a reduced tip element 228 projecting outward therefrom. The body portion of plunger 224 is cylindrical and, in the outer position of the plunger shown, contacts the in-

ner ends of two clutch dogs 229 slidably mounted in bosses 230 and 231 formed integrally with hub 232 of disc 223 and with disc 223 at the periphery thereof, respectively, these bosses and the clutch dogs being aligned diametrically of disc 223. Hub 232 and shaft 216 are provided with aligned bores which slidably receive the inner end portions of the dogs. When the dogs are projected, the tooth elements 233 engage the clutch element 221 of ring member 219, clutching disc 223 and member 219 together for rotation as a unit. An arcuate wire spring 234 passes loosely through dogs 229 and yieldingly urges them toward each other, while also restraining them against turning movement. When the plunger 224 is in its inner position, bringing element 227 thereof opposite the inner ends of dogs 229, the latter are retracted by spring 234 and thereby de-clutched from clutch element 221, at which time the ring member 219 and the disc 223 are free for relative turning movement.

A bracket 235 is suitably secured on the outer end of a thick rib or boss 236 of gear housing 203. An operating lever 237 is rockably mounted on bracket 235, by a pivot pin 238, and extends upward therefrom into contact with tip 228 of plunger 224. Lever 237 is provided at one side thereof with a depending finger 239 held in contact, by spring 227, with a cam member 240 secured upon the rearward end of a control shaft 241 rotatably mounted through the front wall of housing 203 and bracket 235. A suitable handle 242 is secured upon the forward end of shaft 241 in contact with the front wall of housing 203, which may be provided with suitable legends, such as "Fast," "Stop" and "Slow," over which the handle is moved to indicate the proper adjustments of the control means for driving the roll at high speed, stopping it and driving it at low speed.

A pawl 243 is pivoted on bracket 235 and extends upward therefrom into proximity to ratchet element 222 of ring member 219. At its lower end, below and rearward of its pivot, pawl 243 is provided with a forwardly extending tab 244. A wire spring 245 is fixed at its lower end to bracket 235, conveniently by means of one of the mounting screws therefor, from which it extends upward and is bent about the upper end portion of pawl 243, urging the latter toward clutch element 222. The cam member 240 is appropriately formed and has three positions corresponding, respectively, to the "Fast," "Stop" and "Slow" positions of handle 242. When handle 242 is in its "Fast" position, cam member 240 is in its position shown, in contact with tab 244 of pawl 243, holding the latter out of engagement with ratchet element 222, while permitting movement of finger 239 of lever 237 into its inward position and outward movement of the upper end of lever 237 by plunger 224, then held in its projected position by compressing spring 225. In the "Fast" position of cam member 240, the disc 223 and the ring member 219 are clutched together, and the ring member 219 is free to rotate and is locked to spur pinion 218 of gear 215, by a spur pinion 246 rotatably mounted on a stud 247 secured in disc 223 and meshing with pinion 218 and with ring gear 220. The roll shaft 216, and the roll 25, are then driven at high or "Fast" speed from the motor driven stub shaft 44. By turning handle 242 into "Stop" position, the cam member 240 is so disposed as to hold pawl 243 in its released position shown, while also holding finger 239 of lever 237 in its outer po-

sition, thereby holding the upper end of lever 237 in its inner position, so that plunger 224 is then held in its inner or retracted position. The disc 223 is then declutched from the ring member 219, which is free to rotate, and the roll shaft 216 is not driven. When handle 242 is turned to "Slow" position, the cam member 240 is so disposed as to release the pawl 243, which is then moved into engagement with ratchet element 222 and holds ring member 219 against rotation in counterclockwise direction (Figure 12), and to hold finger 239 in its outer position, declutching disc 223 from ring member 219. The pinion 245 is then driven counterclockwise by pinion 217 and travels clockwise around the internal ring gear 220, carrying with it the disc 223 and driving the roll shaft 216 at slow speed. The roll 25 may thus be driven at either high or low speed, or stopped, in the continued operation of the motor 48, by the drive and control means above described.

Bevel gear 215 meshes, at its lower side, with a bevel pinion 250 secured on the upper end of a vertical shaft 251 rotatably mounted through a bushing 252 in bearing boss 256 projecting outward from wall 32a. Shaft 251 is squared at its lower portion, at 254, for reception of a star wheel of an eccentric and clutch assembly 255. Below squared portion 254 the shaft 251 is provided with a reduced cylindrical portion 256 extending into a boss 257 projecting upward from the bottom wall of housing 203, the lower end of shaft 251 seating upon a bearing ball 58. The clutch assembly is similar to that of the Janda Patent No. 1,867,839 and requires no further detailed description. It comprises an eccentric 259 seating upon the upper end of boss 257 and receiving an eccentric strap 260 at the forward end of an arm 261 connected at its rearward end, by a universal connection 262, to the lower end of an arm 263 fixed at its upper end on shoe operating shaft 106.

In Figures 11 and 12 the parts are shown in the positions they occupy when the shoe has been moved to the roll. The clutch means of the assembly 255 is controlled by a trip finger 264 pivoted on a lug 265 projecting from the front wall of housing 203, this finger normally being disposed for contact with one of the tabs 118 (in the same manner as in Figure 8) for declutching the eccentric 259 from shaft 251. A rod 266 is connected to the inner end of finger 264 and extends therefrom upward through boss 238 into a hollow boss 267 at the top of housing 203, which receives a button 268 secured on the upper end of rod 266. Button 268 normally is held raised by a compression spring (not shown) confined between the button and the bottom wall of boss 267, in a known manner, so as to hold the outer end of finger 264 depressed into contact with assembly 255 in the path of travel of tabs 118 so as to be contacted thereby. When button 268 is depressed, the outer end of finger 264 is raised into clutch releasing position, the eccentric 259 is clutched to the shaft 251 for rotation therewith, and upon completion of one half revolution of the eccentric one of the tabs 118 contacts finger 264 thereby declutching eccentric 259 from shaft 251. In that manner, shoe operating shaft 106 is rocked in alternately opposite directions for moving the shoe 26 to and from the roll 25, as has previously been explained. Since the assembly 255 rotates about a vertical axis, the clutch disc 125 will remain in its outer

position without provision of the plunger 143 of Figure 8. In that respect, as well as in having the eccentric contiguous to the disc receiving the tension spring, the assembly 255 of Figures 11 to 13, inclusive, differs from the clutch and eccentric assembly of Figures 2 and 6 to 8, inclusive, assembly 255 being similar to the eccentric and clutch assembly of Janda Patent No. 1,867,839, as noted.

A release lever 269 is pivoted at its upper end on pin 238 and straddles the lower portion of lever 237, extending downward into proximity to the eccentric and clutch assembly 255. A set screw 270 is adjustably secured through the upper end of lever 269, in position to contact the outer face of lever 237 above pin 238. Lever 269 is further provided with a rearwardly offset and inwardly extending trip finger 273 overlying pawl 243 and disposed to move the latter from its holding position to its releasing position and to hold it in its latter position, when lever 269 is swung counterclockwise about pin 238 from its inner position of Figure 11 to its outer position. A cupped cam plate 271 is secured on the upper face of assembly 255 for rotation therewith, and is provided with a cam element 272 projecting radially outward therebeyond. The cam element is disposed to contact the lower end of arm 269 as the assembly is turned into the position which it occupies when the shoe 26 has been moved rearward away from the roll. That swings lever 269 outward and, through screw 270, swings lever 237 inward so as to declutch disc 223 from ring member 219, while also moving pawl 243 into releasing position and holding there, or preventing movement of pawl 243 to holding position if it is already in releasing position. In that manner rotation of the roll 25 is stopped automatically when the shoe is moved from the roll. When the assembly 255 is turned through the succeeding half revolution, the cam element 272 is moved clear of the lower end of lever 269 and the parts are returned to the positions they occupied prior to outward movement of lever 269. Accordingly, if the roll 25 was being driven at either "Fast" or "Slow" speed, when the shoe 26 was moved away from roll 25, the drive of the latter at the selected speed will be reestablished automatically upon return of the shoe to the roll. Likewise, if the roll 25 was not being driven when shoe 26 was moved rearward, it will not be driven upon return movement of the shoe. That is advantageous, in that by setting the handle 242 at "Stop" position, the shoe 26 may be moved to and from the roll 25, while the latter remains stationary, when it is desired to use the machine for pressing suits and like articles, instead of for ironing.

As above indicated, and as will be understood by those skilled in the ironing machine art, changes in construction and arrangement of the parts of the ironing machines of my invention may be resorted to without departing from the field and scope thereof, and I intend to include all such variations, as fall within the scope of the appended claims, in this application in which the preferred forms only of my invention are disclosed.

I claim:

1. In an ironing machine, a support, a gear housing secured to said support extending thereabove, a motor comprising a casing open at its ends secured to said housing extending inward therefrom over said support and having its outer end communicating with atmosphere, an imper-

forate supporting sleeve open at both ends secured to the inner end of said motor casing, a roll driven by said motor mounted for rotation on said sleeve and said motor casing supported thereby and housing said motor, and a fan driven by said motor and communicating with the space within said sleeve and said motor casing effective for causing flow of air therethrough.

2. In an ironing machine, a support, a gear housing secured to said support extending thereabove provided at its inner side with a passage opening to atmosphere, a tubular roll supporting structure comprising a motor having a casing secured at its outer end to the inner side of said housing and an imperforate sleeve secured to the inner end of said casing, the latter and said sleeve being open at their ends with said motor casing opening at its outer end into said passage, said structure extending inward from said housing over said support, a roll supported by and mounted for rotation on said structure spaced therefrom and housing said motor, a fan within said structure secured on the shaft of said motor and communicating with the space between said structure and said roll, a cooperating shoe movable to and from said roll, and means driven by said motor for driving said roll and operating said shoe.

3. In an ironing machine, a support, a gear housing secured to said support extending thereabove, a tubular roll supporting structure comprising a motor having a casing secured at its outer end to the inner side of said housing and an imperforate sleeve secured to the inner end of said casing, said structure being open at its ends for flow of air lengthwise therethrough and extending inward from said housing over said structure, a perforated roll supported by and mounted for rotation on said structure radially spaced therefrom with the space between said structure and said roll closed substantially air tight at its ends, said structure housing said motor and having openings into said space, a fan within said structure driven by said motor effective for causing air flow through said structure and thereby inducing air from said space through said openings, a cooperating shoe movable to and from said roll, and means driven by said motor for driving said roll and operating said shoe.

4. In an ironing machine, a support, a gear housing secured to said support extending thereabove provided at its inner side with a passage opening to atmosphere, a tubular roll supporting structure comprising a motor casing open at its ends secured at its outer end to the inner side of said housing in communication with said passage and an imperforate lengthwise tapering sleeve open at its ends secured to the inner end of said casing, a perforated roll supported by and mounted for rotation on said structure radially spaced therefrom with the space between said structure and said roll closed substantially air tight at its ends, said structure housing said motor and having openings into said space at the area thereof of greater extent radially of said structure, a fan within said structure secured on the shaft of said motor effective for causing air flow through said structure and thereby inducing air from said space through said openings, a cooperating shoe movable to and from said roll, and means driven by said motor for driving said roll and operating said shoe.

5. In an ironing machine, a support, a gear housing secured to said support extending there-

above provided at its inner side with a passage opening to atmosphere, a tubular roll supporting structure comprising a motor casing open at its ends secured at its outer end to the inner side of said housing in communication with said passage and an inwardly flaring imperforate sleeve open at its ends secured to the inner end of said casing, a perforated roll supported by and mounted for rotation on said structure radially spaced therefrom with the space between said structure and said roll closed substantially air tight at its ends, said structure housing said motor and said motor casing having adjacent its outer end openings into said space, the latter being otherwise closed to said supporting structure, a fan within said structure secured on the shaft of said motor and disposed to cause flow of air through said structure and across said openings thereby inducing air through the latter from said space, a cooperating shoe movable to and from said roll, and means driven by said motor for driving said roll and operating said shoe.

6. In an ironing machine, a gear housing, a motor secured to said housing, a roll extending about and housing said motor mounted for rotation about a fixed axis, a main drive shaft substantially coaxial with the shaft of said motor driven thereby and extending into said gear housing, a countershaft substantially perpendicular to and driven by said main shaft, a roll drive shaft, means for optionally establishing driving connection between said countershaft and said roll drive shaft, a cooperating shoe movable to and from said roll, a rockably mounted shoe operating shaft, a sleeve loose on said countershaft comprising an eccentric, half-revolution clutch means for clutching and declutching said countershaft to and from said sleeve, and operating connections between said eccentric and said shoe operating shaft.

7. In an ironing machine, a gear housing, a motor secured to said housing, a roll extending about and housing said motor mounted for rotation about a fixed axis, a main drive shaft substantially coaxial with the shaft of said motor driven thereby and extending into said gear housing, a substantially horizontal countershaft substantially perpendicular to and driven by said main shaft, a roll drive shaft, means for optionally establishing driving connection between said countershaft and said roll drive shaft, a cooperating shoe movable to and from said roll, a rockably mounted shoe operating shaft, a sleeve loose on said countershaft comprising an eccentric, half-revolution clutch means for clutching and declutching said countershaft to and from said sleeve, and operating connections between said eccentric and said shoe operating shaft.

8. In an ironing machine, a gear housing, a motor secured to said housing, a roll extending about and housing said motor mounted for rotation about a fixed axis, a main drive shaft substantially coaxial with the shaft of said motor driven thereby and extending into said gear housing, a substantially horizontal countershaft substantially perpendicular to and driven by said main shaft, a roll drive shaft, a cooperating shoe movable to and from said roll, a rockably mounted shoe operating shaft, a sleeve loose on said countershaft with the latter extending through said sleeve from one end and projecting beyond the other end thereof, means for optionally establishing driving connection between said countershaft and said roll drive shaft compris-

ing clutch means on said portion of said countershaft projecting beyond said sleeve, an eccentric fixed on said sleeve, half-revolution clutch means at said other end of said sleeve for clutching and declutching said countershaft to and from said sleeve, and operating connections between said eccentric and said shoe operating shaft.

9. In an ironing machine, a gear housing, a motor secured to said housing, a roll extending about and housing said motor mounted for rotation about a fixed axis, a main drive shaft substantially coaxial with the shaft of said motor driven thereby and extending into said gear housing, a substantially horizontal countershaft overlying and substantially perpendicular to said main shaft, a gear on said countershaft driven by said drive shaft, a roll drive shaft, means for optionally establishing driving connection between said gear and said roll drive shaft, a cooperating shoe movable to and from said roll, a rockably mounted shoe operating shaft, and means comprising an eccentric and a half-revolution clutch for operating said shoe for said gear.

10. In an ironing machine, a gear housing, a motor secured to said housing, a roll extending about and housing said motor mounted for rotation about a fixed axis, a main drive shaft substantially coaxial with the shaft of said motor driven thereby and extending into said gear housing, a substantially horizontal countershaft overlying said main shaft substantially perpendicular thereto, a gear on said countershaft driven by said drive shaft, multiple speed means for optionally establishing driving connection between said gear and said roll comprising a second gear meshing with said first gear, a substantially vertical shaft, a gear secured on the latter shaft and meshing with said second gear, a cooperating shoe movable to and from said roll, a rockably mounted shoe operating shaft, an eccentric disposed about said vertical shaft having operating connection to said shoe operating shaft, and half-revolution clutch means for clutching and declutching said eccentric to and from said vertical shaft.

11. In an ironing machine, a support, a roll and a cooperating shoe overlying said support, a rockably mounted shoe operating shaft, means for coupling said shoe to said shaft for movement thereby to and from said roll and for uncoupling it from said shaft for movement independently thereof away from said roll, shoe operating control means comprising an actuating member disposed at the front of said support adjacent one end thereof, and means for effecting coupling and uncoupling of said shoe to and from said shaft comprising a release and coupling member disposed at the front of said support adjacent the other end thereof, said actuating member being movable toward said one end of said support for initiating operation of said shoe and yieldingly urged toward said other end of said support, and said release and coupling member being movable toward said other end of said support for effecting the shoe uncoupling operation and toward said one end of said support for effecting the shoe coupling operation.

12. In an ironing machine, a support, a roll and a cooperating shoe overlying said support, a rockably mounted shoe operating shaft, means for coupling said shoe to said shaft for movement thereby to and from said roll and for uncoupling it from said shaft for movement inde-

pendently thereof away from said roll, shoe operating control means comprising an actuating member disposed at the front of said support adjacent one end thereof in position to be actuated by one knee of an operator seated in front of said support, and means for effecting coupling and uncoupling of said shoe to and from said shaft comprising a release and coupling member disposed at the front of said support adjacent the other end thereof in position to be moved in releasing direction by the other knee of the operator, said actuating member being movable toward said one end of said support for initiating operation of said shoe and yieldingly urged toward said other end of said support, and said release and coupling member being movable toward said other end of said support for effecting the shoe uncoupling operation and toward said one end of said support for effecting the shoe coupling operation.

13. In an ironing machine, a support, a roll and a cooperating shoe in back of said roll overlying said support, a rockably mounted shoe operating shaft, a shoe supporting arm loose on said shaft, an operating arm fixed on said shaft, means for coupling and uncoupling said supporting arm to and from said operating arm comprising a member pivoted on said supporting arm for movement about an axis extending transversely thereof, means holding said member against movement relative to the supporting arm in coupling direction when said member is in uncoupling position and for releasing said member from said supporting arm as it reaches coupling position in the movement of said supporting arm from its released position forward into its coupled position, a coupling and release arm having an angular slot therein pivoted on said support for swinging movement toward and away from said shaft, and a pin secured to said coupling member operating in said slot cooperating with said coupling and release arm for uncoupling said supporting arm from said operating arm and swinging it away from said roll and for swinging said supporting arm toward said roll into cooperating relation to said operating arm and coupling it to the latter.

14. In an ironing machine, a support, a roll and a cooperating shoe in back of said roll overlying said support, a rockably mounted shoe operating shaft, a shoe supporting arm loose on said shaft, an operating arm fixed on said shaft, means for coupling and uncoupling said supporting arm to and from said operating arm comprising a member pivoted on said supporting arm for movement about an axis extending transversely thereof, means holding said member against movement relative to the supporting arm in coupling direction when said member is in uncoupling position and for releasing said member from said supporting arm as it reaches coupling position in the movement of said supporting arm from its released position forward into its coupled position, a coupling and release arm having operating connection to said coupling member effective for uncoupling said supporting arm from said operating arm and swinging it away from said roll and for swinging said supporting arm toward said roll into cooperating relation to said operating arm and coupling it to the latter, and means for operating said coupling and release arm comprising an actuating member pivoted for movement about a vertical axis and disposed at the front of said support in position to be moved in shoe uncoupling direc-

tion by the knee of an operator seated at the front of said machine.

15. In an ironing machine, a support, a roll and a cooperating shoe in back of said roll overlying said support, a rockably mounted shoe operating shaft, a shoe supporting arm loose on said shaft, an operating arm fixed on said shaft, means for coupling and uncoupling said supporting arm to and from said operating arm comprising a member pivoted on said supporting arm for movement about an axis extending transversely thereof, means holding said member against movement relative to the supporting arm in coupling direction when said member is in uncoupling position and for releasing said member from said supporting arm as it reaches coupling position in the movement of said supporting arm from its released position forward into its coupled position, a coupling and release arm having operating connection to said coupling member effective for uncoupling said supporting arm from said operating arm and swinging it away from said roll and for swinging said supporting arm toward said roll into cooperating relation to said operating arm and coupling it to the latter, and means for operating said coupling and release arm comprising an actuating

member pivoted for movement about a vertical axis and disposed at the front of said support in position to be moved in shoe uncoupling direction by the knee of an operator seated at the front of said machine and means for cushioning rearward movement of said supporting arm.

HENRY H. BABCOCK.
